UNITED STATES PATENT OFFICE.

THOMAS H. BOLMER, OF NEW YORK, N. Y.

UTILIZING GASEOUS EXPLOSIONS AS A MOTIVE FORCE.

SPECIFICATION forming part of Letters Patent No. 379,674, dated March 20, 1888.

Application filed June 1, 1887. Serial No. 239,950. (No model.)

To all whom it may concern:

Be it known that I, THOMAS H. BOLMER, of the city, county, and State of New York, have invented a new and useful Improvement in Utilizing Gaseous Explosions as a Motive Force, of which the following is a full, clear, and exact description.

This invention, which is applicable to the propulsion of vessels, imparting driving-power to wheels or motors of various kinds, and to pumping and other purposes, relates to apparatus in which gaseous explosions in a close chamber having a suitable outlet or outlets are utilized to obtain the motive force, any suitable simple or compound gas being used, including various explosive compounds, either gaseous, liquid, or solid, and any suitable means being employed for igniting or exploding the same, including both electrical means and a gas or other flame. Electrical appliances, however, are preferred.

The invention consists in certain novel combinations of parts or devices in an apparatus of this description, substantially as hereinafter described, and pointed out in the claims.

For the purpose of illustration the invention here will be described as adapted to propelling vessels by, as in other apparatuses operating by gaseous explosions, causing the gas to act upon water within a tube arranged below the water-level and open at its end or ends to the surrounding body of water for the purpose of obtaining the necessary resistance whereby to propel the vessel. I will also describe, for convenience' sake, the using of two gases in separate receptacles—as, for instance, hydrogen and oxygen or hydrogen and atmospheric air—that require to be mixed or brought together before the same can be ignited to produce the explosion.

Reference is to be had to the accompanying drawings, forming a part of this specification, in which similar letters of reference indicate corresponding parts in both the figures.

Figure 1 represents a longitudinal vertical section of an apparatus embodying my invention, and Fig. 2 a plan of the same.

A is the explosion-chamber, and B B' pipes or tubes connected therewith on opposite sides and designed to extend, respectively, the one through or near the stern of a floating vessel and the other through or toward the bow end

thereof. These tubes, which are open at their ends, are both arranged below the water line or level of the vessel.

C C' are the separate gas tanks, connected with the chamber A by separate pipes b b', controlled by cocks or valves c c'. The tubes B B' are each fitted with a weighted or self-closing valve, D D', arranged so that the one valve closes toward the chamber A and the other valve opens toward it. By this arrangement, and supposing the valves D D' to open, respectively, in the directions indicated in the drawings, when an explosion of the gas or gases takes place in the chamber A, water which entered by the pipe B will be expelled through the pipe B' the valve D' then opening and the valve D closing by the pressure of the exploded gas to prevent egress through it. This will cause the vessel to be propelled in a reverse direction to that indicated by the arrows x x. Immediately, however, after the impulse has been given to the water in or through the pipe B' a reaction takes place by the formation of a vacuum or partial vacuum as caused by the spent gas or gases in the chamber A. This will cause the valve D' to close and prevent the return of water through it, and the other valve, D, to open, which will produce a sucking action on the water in the pipe B, that will aid in the propulsion of the vessel and serve to resupply the chamber A and inner portion of the tube B' with water for another and subsequent explosion of the gas or gases in the chamber A, the several explosions being intermittent and at suitable intervals apart.

The valves D D' are arranged within rotatable plugs e e, having a transverse passage through them, and situated within cases or boxes f f, that couple divided sections of the tubes B B', so that upon turning these plugs e e half round the valves D D' will have a reverse opening and closing action relatively to the chamber A, for the purpose of reversing the motion of the vessel, by converting the tube B' into an inlet one for the water and the tube B into an outlet or discharge one. Said plugs e e may be thus operated as required by means of a sliding rack, g, actuated by a lever, s, and pinions or partial pinions h h, fast to the plugs and gearing with said rack.

The cocks or valves c c', which shut off and open the supply of gas intermittently to the

chamber A, are geared together—as, for instance, by toothed sections *i i*—to both open and both close simultaneously, so as to furnish the necessary intermittent supply of both 5 gases—that is, when two gases are used to produce the explosion. These valves *c c'* may be operated by hand or automatically by any suitable power.

G is a dynamo or electric battery for exploding the gas or gases in the chamber A by a spark emitted between the two poles *k k* upon the circuit being closed by a switch, *l*, applied to one of the two wires *m m*. This switch is connected—as, for instance, by a rod, *n*—with 15 one of the coupled valves *c c'*, so that as said valves are opened to supply the chamber A with gas the switch will be operated and the circuit be opened or broken, and as said valves are closed the switch will also be closed and 20 the circuit be made to ignite the gases in the chamber A. The chamber A may be of any suitable height.

Of course different means may be used for charging the chamber A with the exploding 25 gas or gaseous compound and for igniting the same, as hereinbefore remarked.

To illustrate one of the many other purposes to which the invention may be applied, supposing the apparatus to be constructed as 30 shown, it may, for instance, be used to ad-

vantage for pumping purposes and will operate both as a suction and force pump.

Having thus described my invention, what I claim as new, and desire to secure by Letters Patent, is—

1. In apparatus for transmitting motive power by a current of liquid, the combination, with an explosion-chamber, one or more pipes and one or more valves controlling the same for introducing an explosive material or compound to said chamber at regular intervals, and igniting connections for exploding said material or compound within said chamber, of two tubes connected with said chamber, through which the liquid used for transmitting motive power is admitted and ejected, and reversely-acting valves capable of adjustment to act either as inlet or outlet valves of said liquid, essentially as herein set forth. 40

2. The combination, with the explosion-chamber A, of the tubes B B', connected therewith on reverse sides of said chamber, and the reversely-operating valves D D', capable of adjustment to act either as inlet or outlet valves, substantially as specified. 45
